David Evins, 151 W. 26th St.,
New York, N.Y. 10001

Filed June 28, 1967, Ser. No. 7,625

Term of patent 7 years

(Cl. D2—325)

FIG. 1

FIG. 2

FIG. 1 is a perspective view of a heel or similar article showing my new design.

FIG. 2 is a bottom view thereof.

The opposite side of the heel as shown in FIG. 1 is substantially the same. The shape of the heel is the same all around as shown in FIGS. 1 and 2.

A conventional shoe is shown in broken lines for environmental purposes.

I claim:

The ornamental design for a heel or similar article, substantially as shown and described.
